UNITED STATES PATENT OFFICE.

LEVI S. DAVIS, OF CANISTEO, NEW YORK.

APPARATUS FOR MANUFACTURING GAS.

SPECIFICATION forming part of Letters Patent No. 637,856, dated November 28, 1899.

Application filed August 9, 1897. Serial No. 647,591. (No model.)

To all whom it may concern:

Be it known that I, LEVI S. DAVIS, a citizen of the United States, residing at Canisteo, Steuben county, New York, have invented 5 certain new and useful Improvements in Gas-Generators, of which the following is a specification.

This invention relates to certain new and useful improvements in apparatus for the 10 manufacture of gas, having for its object to improve such apparatus generally and to prevent waste of the hydrocarbon liquid employed in the manufacture and the formation of lampblack and tarry matter. With these 15 objects in view the invention consists in the method and apparatus hereinafter more fully described.

In the accompanying drawings, illustrating 20 the invention, Figure 1 is a longitudinal sectional elevation of the improved apparatus used in carrying the invention into effect, and Fig. 2 is a detail sectional view of the generator.

The apparatus employed may be constructed 25 in various ways; but preferably it is built of masonry to form a generator A and a fixing-chamber B, which latter communicates through a pipe a with a suitably-constructed scrubber. (Not shown.)

30 The generating-chamber A² is preferably contracted at its upper end and is provided with the usual peep-holes a² and at its lower end with a coal-bed to support a charge of coal b, which is maintained by means of a 35 suitable feeder c, and an air-pipe d, leading from a blower C, is arranged to deliver an air-blast upwardly through the coal-bed. Extending centrally through the body of coal to a point immediately above the same is a pillar 40 of masonry, through which extends an oil-pipe f, from which leads a series of radial branch pipes f', terminating at the top of the pillar in spray-nozzles f², adapted to direct a spray of heated hydrocarbon vapor upwardly

45 through the generating-chamber, but out of contact with the walls thereof. The air-pipe d likewise extends through the pillar or wall and has leading therefrom a series of horizontal radially-arranged branch pipes d', which 50 open into the generating-chamber at points

just above the base of the pillar and deliver air uniformly to the coal-bed.

Heretofore it has been customary to introduce a hydrocarbon vapor horizontally into a generating-chamber above the coal-bed or 55 to introduce it horizontally into the chamber from a central partition; but as it is necessary that such vapor shall be thrown entirely across the chamber in order to bring it into intimate contact with the entire volume of gases 60 from the coal it has been impossible to prevent the vapor from striking the opposite walls and breaking up, resulting in the burning of the vapor and the formation of lampblack and of tarry substances, and thus increasing the 65 consumption of the vapor and impairing the quality of the resulting gas. These disadvantages are overcome by the use of the present invention, as by the introduction of the hydrocarbon into the generating-chamber 70 with the current of gases in a vertical spray it is caused to flow upwardly in the direction of flow of the gases from the coal without disturbing such flow and without being thrown against the inner walls of the chamber. A 75 very much smaller quantity of vapor is thus required in the manufacture of gas, and the quality of the gas is materially improved.

The fixing-chamber B is formed with a sinuous channel e, which communicates at the 80 upper end with the generating-chamber and through the pipe a with a scrubber or gasometer, as desired.

The oil-supply pipe extends in coils through 85 the walls of the fixing-chamber in close proximity to the channel e in order to heat the oil before it is introduced into the generating-chamber A², and this pipe communicates with a pump D, by means of which the oil is forced through the pipe into the generating-chamber. 90 The pump in turn communicates with a suitable oil-supply tank E, and intermediate this tank and the pump is a measuring vessel F, from which water is introduced into the oil previous to its being drawn into the pump 95 through a passage controlled by a cock h, by means of which cock the relative proportions of oil and water are regulated. Intermediate the pump and the coils of the oil-supply pipe f may be arranged a suitable meter G to regu- 100

late the quantity of fluid flowing through said pipe to the generating-chamber.

By the introduction of water into the oil the quality of the gas is improved and the liability 5 of the oil being burned is also lessened.

Without limiting myself to the construction and arrangement of the parts shown and described, what I claim is—

1. In an apparatus for the manufacture of 10 gas, the combination of a generator and a fixing-chamber, an air-pipe communicating with the lower end of the generator and with a blower, an oil-supply pipe provided with a nozzle arranged centrally of the generating-chamber to direct a heated hydrocarbon vapor vertically through the chamber, and a measuring vessel communicating with the oil-supply pipe through a valve-controlled passage, substantially as described.

2. In an apparatus for the manufacture of 20 gas, the combination of a generator and a fixing-chamber, an air-pipe communicating with the lower end of the generator and with a blower, an oil-reservoir, and an oil-supply

pipe communicating therewith and provided 25 with a nozzle arranged centrally in the generating-chamber to direct a heated hydrocarbon vapor vertically upward through the chamber, substantially as described.

3. In an apparatus for the manufacture of 30 gas, the combination of a generator provided at its bottom with a pillar or wall, a series of oil-supply pipes extending through said pillar and opening into the generator, a source of oil-supply connected to said pipe, a series of 35 laterally-extending air-supply pipes projecting through the walls of the pillar below the top thereof, and a fan or blower communicating with said air-pipes, substantially as described. 40

In testimony whereof I have signed my name to this specification in the presence of two subscribing witnesses.

LEVI S. DAVIS.
